UNITED STATES PATENT OFFICE.

LEVI SAMUEL HOON, OF BUTLER, PENNSYLVANIA, ASSIGNOR OF ONE-HALF TO GEORGE C. BELLIS, OF BUTLER, PENNSYLVANIA.

METHOD OF CLEANING OIL-WELLS.

1,325,293.

Specification of Letters Patent. Patented Dec. 16, 1919.

No Drawing.

Application filed May 26, 1919. Serial No. 299,896.

To all whom it may concern:

Be it known that I, LEVI SAMUEL Hoon, a citizen of the United States, residing at Butler, county of Butler, and State of Pennsylvania, have invented a new and useful Improvement in Methods of Cleaning Oil-
Wells, of which the following is a full, clear, and exact description.

This invention relates to a method of removing the incrustation of wax, etc., from oil wells, to open the pores which have been clogged up by this incrustation, as well as from the pumps in the well.

One of the objects of my invention is to provide a simple and efficient method whereby this incrustation will readily and quickly be dissolved from the pores of the well, and which can be pumped from the well in a fluid state.

As is well known to those familiar with the art, a large number of oil wells after they have been pumped for sometime become clogged by the paraffin wax and other heavy matter in the oil, so that the flow of the oil to the well gradually diminishes.

I have discovered that this incrustation can readily be removed by pouring into the well a solvent or cutting agent, together with an agent which when combined with the solvent agent will simultaneously heat and agitate the solvent, which will not only cut the wax, but it will force the solvent into the pores of the well, to thoroughly cleanse the same.

I am aware that it has been proposed to use an alkaline solvent, together with acids which were intended to heat upon the solvent and cause the same to loosen the wax.

In carrying out my invention I mix up an alkaline solution, pump as much of the oil from the well as possible, then pour a sufficient quantity of this solution into the well, either on the outside or through the pump tubing or barrel, and during the pouring of this solution, or immediately thereafter, I drop into the well a suitable quantity of heating and agitating material, which when it combines with the solvent will quickly heat up the solvent and agitate the same during the chemical reaction. I then pour in about one-half barrel of water, which is preferably heated, to wash the solution into the well and to provide a sufficient quantity of water, and then follow up with sufficient oil to fill the shot hole. The action of these

combined materials will quickly cut the paraffin from the pores of the well, and will also melt a great portion of the paraffin which will mix with the oil so that it can be readily pumped from the well, together with the solution in a very short period after the material has been poured into the well.

The solvent which I prefer to use I make up of about the following proportions:

5 gallons of water,
10 pounds of caustic soda; and
About 1 pound of sal-ammoniac.

I may, however, use the solution without the sal-ammoniac. During the pouring of approximately the above amount of solution into the well, I combine therewith, or deposit into the well immediately thereafter, about two pounds of carbid, and which when combined with the water will throw out acetylene gas and which chemical action will heat the solvent together with any of the oil in the well to a very high temperature, and also cause the same to be agitated violently, which will force the solution into the pores of the well and free the incrustation therefrom.

I have successfully cleaned a large number of wells with the above process, and materially increased the flow of all wells which I have cleaned, without injury to the pumps or valves.

It will readily be understood by those familiar with the art that the amount of solution required for cleansing the well is dependent upon the size of the well, and it will also be appreciated that changes may be made in the specific proportions as well as the ingredients.

The advantages of my invention result from the provision of the method of cleaning oil wells, whereby I am enabled to free and dissolve the paraffin by means of a combined solvent and air agent which acts to simultaneously heat and agitate the solvent.

I claim:

1. The method of cleaning wells, comprising the steps of pouring a crust-cutting solution into the well to be cleaned, together with a gas producing agent for simultaneously heating and agitating the material in the well.

2. The method of cleaning wells, comprising the steps of pouring an alkaline solution, together with an agent for simul-

taneously heating and agitating the material in the well, which agent is such that it will not counteract the action of the solution.

5. 3. The method of cleaning wells, comprising the steps of pouring a solution of water and caustic soda into the well, together with a gas producing agent for simultaneously heating and agitating the solution in the well.

10. 4. The method of cleaning oil wells, comprising the steps of pouring a solution of water, caustic soda and sal-ammoniac into the well, and also combining carbide therewith, to simultaneously heat and agitate the solution in the well.

15. 5. The method of cleaning oil wells, comprising the steps of pouring a solution made up of five gallons of water, 10 pounds of 20 caustic soda, and 1 pound of sal-ammoniac

into the well, together with approximately 2 pounds of carbide with the above amount of material.

6. The method of cleaning wells, comprising the steps of pouring a solution of water 2 and caustic soda into the well, together with carbide for simultaneously heating and agitating the solution within the well, substantially as described.

7. The method of cleaning wells, comprising the steps of pouring a solution of water and caustic soda into the well, together with an agent for simultaneously heating and agitating the solution within the well, which agent is such that it will not counteract 3 the action of said solution, substantially as described.

In testimony whereof I have hereunto set my hand.

LEVI SAMUEL HOON.
